UNITED STATES PATENT OFFICE.

WALTER E. LOMBARD, OF ARLINGTON, MASSACHUSETTS, ASSIGNOR TO A. O. NORTON, INC., OF BOSTON, MASSACHUSETTS, A CORPORATION OF MAINE.

GOVERNOR MECHANISM FOR LIFTING-JACKS.

1,384,202.

Specification of Letters Patent. Patented July 12, 1921.

Application filed August 2, 1920. Serial No. 400,824.

To all whom it may concern:

Be it known that I, WALTER E. LOMBARD, a citizen of the United States of America, and a resident of Arlington, in the county of 5 Middlesex and State of Massachusetts, have invented certain new and useful Improvements in Governor Mechanism for Lifting-Jacks, of which the following is a specification.

10 This invention relates to governor mechanism for lifting jacks and particularly to that class of screw jacks which are adapted to lower under the weight of the load, the object of the invention being to provide a simple and effective means for controlling the speed of the lowering member and insuring its rotation at a uniform speed.

One of the objects of the invention is to locate the one-way driving connection between the worm shaft and the main operating shaft at a point where it is accessible 20 when it is desired to repair the same.

The invention consists in loosely mounting 25 on a driving shaft the worm gear coacting with the governor actuating worm and securing to said driving shaft a disk carrying pawls adapted to coact with a ratchet revoluble with said worm gear whereby said worm gear will be driven in one direction 30 only and this during the lowering of the load.

The invention further consists in certain 35 novel features of construction and arrangement of parts which will be understood readily by reference to the description of the drawings and to the claims to be hereinafter given.

For the purpose of illustrating the invention, one preferred form thereof is illustrated in the drawings, this form having 40 been found to give satisfactory and reliable results although it is to be understood that the various instrumentalities of which the invention consists can be variously arranged 45 and organized and the invention is not limited to the precise arrangement and organization of these instrumentalities as herein shown and described, except as required by the scope of the appended claims.

50 Of the drawings:

Figure 1 represents a vertical section of a lifting jack embodying the principles of the present invention.

Fig. 2 represents a horizontal section on 55 line 2, 2, on Fig. 1.

Fig. 3 represents an enlarged vertical section of the one-way driving connection adapted to rotate the worm gear in one direction only.

Fig. 4 represents a section on line 4, 4, on 60 Fig. 3.

Fig. 5 represents a vertical section showing the governor mechanism in elevation.

Fig. 6 represents a vertical section showing the manually controlled brake mechanism, and 65

Fig. 7 represents an elevation of the actuator for removing the brake arms from the brake wheel.

Similar characters indicate like parts 70 throughout the several figures of the drawings.

In the drawings, 10 represents a suitable base supporting a stationary standard 11 over the outer periphery of which is fitted a 75 movable sleeve 12, to the upper end of which is threaded a cap 13.

In the upper end of the standard 11 is mounted a nut 14 to which is threaded a lifting screw 15 having splined to its upper reduced end a bevel gear 16 with which meshes a bevel gear 17 formed upon or secured to a revoluble shaft or spindle 18, the outer end of which is provided with a suitable operating mechanism 19 of any well-known construction. 85

Between the upper face of the bevel gear 16 and the inner face of the cap 13 are two annular plates 20, 21, between which are interposed a plurality of anti-friction members 22. 90

The movable member 12 is provided on one side with a flanged projection 24 having a removable plate 25 secured thereto by bolts 25*. 95

The plate 25 is provided with a bearing 26 for the spindle or shaft 18 and secured to the shaft is a gear 27 revoluble with said shaft in either direction.

Beneath the gear wheel 27 is a revoluble 100 driving shaft 28 having secured thereto a pinion 29 meshing with said gear 27 and driven thereby in either direction.

The shaft 28 has loosely mounted thereon, a worm wheel 30 which meshes with a worm 105 31 revoluble in bearings 32 in the bracket 33 secured to the inner face of the removable plate 25.

To the reduced end 41 of the worm 31 is secured a brake disk or wheel 42 with the 110

periphery of which coacts two brake members 43 pivoted at 44 to the bracket 40.

The lower end of each brake member 43 is provided with a recess 45 in which is positioned one end of a helical spring 46 the opposite ends of said springs being disposed in the recesses 47 and 48 in the removable plate 25 and bracket 40.

Between the lower adjacent ends of the 10 brake members 43 is positioned a flat sided projection 49 formed upon the actuating lever 50.

A portion of the flat sided projection 49 is cylindrical and positioned in a cylindrical 15 hole in the flange of the removable plate 25.

The springs 46 normally retain the brake members in contact with the periphery of the disk 42 and prevent its rotation until the actuating lever 50 is moved to cause said flat 20 sided projection 49 to separate said brake members 43 and remove them from contact with the disk 42.

The worm 31 is provided at its opposite end with a reduced end 51 to which is secured a disk 52 having mounted thereon two 25 slideable members 54, the outer ends of which have broad bearing flanges 55, the outer 30 faces of which are curved to fit the cylindrical wall 56 of a chamber formed in the bracket 40.

The inner face 57 of the flange 55 is flat and forms a bearing surface for the cam 35 projection 58 on the lever 60 pivoted at 61 and provided on its free end with the weight 62.

This governor is the same and operates in the same manner as that shown and described in U. S. Patent No. 1,324,346 issued to Frank L. Gormley, Dec. 9, 1919, to which 40 reference may be made for details of construction.

The removable cover plate 25 is provided with semi-cylindrical recesses 67, 68 into which portions of the governor and brake 45 mechanism project.

When the cover plate 25 is removed from the flanged projection 24 all of the devices for controlling the lowering of the movable member 12 are removed therewith.

50 The shaft of worm 31 is provided with an anti-friction device 72 adapted to take care of the end thrust of the worm 31 during the lowering of the jack.

The driving shaft 28 has keyed or otherwise secured thereto, a disk 73 having projecting lugs 74 to the ends of which is secured a ring 75 by means of screws 76.

Interposed between the ring 75 and the disk 73 are a plurality of pawls 77 each pivoted at 78 and having the outer ends thereof pressed inwardly by helical springs 79 into contact with the teeth of the ratchet 80 secured to the hub of the worm gear 30.

The reduced outer end 81 of the driving 65 shaft 28 has a bearing in a cylindrical socket

82 formed in a removable member 83 threaded to the cover 25 as indicated in Fig. 1 of the drawings.

This plate or member 83 is cylindrical and of a diameter somewhat greater than the 70 diameter of the worm gear 30 so that when the member 83 is removed from the cover plate 25 the disk 73, worm gear 30, and shaft 28 may be readily removed from the casing 75 of the jack without disturbing other parts thereof.

This is of great convenience as usually there is more trouble with the one-way driving connection than with any other part 80 of the jack.

This provides a means whereby this connection may be removed at any time for repair.

In the operation of the device, the gear 27 is rotatable with the operating shaft 18 in 85 either direction and consequently the shaft 28 rotates in either direction during the raising and lowering of the load.

When the load is being raised however, the pawls 77 ride over the teeth of the ratchet 80 and consequently no motion is imparted to the worm gear 30 which is loosely mounted upon the shaft 28 and normally is prevented from turning by means of the 90 thread of the worm 31.

When the load is being lowered, however, under its own weight the pawls 77 will engage the teeth of the ratchet 80 and rotate the worm gear 30 which in turn will cause the rotation of the worm on which the 100 governor mechanism and brake wheel are both mounted.

Obviously the pitch of the thread of the worm 31 must be of such inclination as will permit said worm to be revolved about its 105 axis when the worm gear 30 is rotated about the axis of the driving shaft 28 during the lowering operation.

Should the worm 31 start to rotate at an excessive speed under the weight of the load, 110 the members 60 will be thrown outwardly by centrifugal force causing the shoes 55 to be moved into frictional engagement with the cylindrical wall 56 of the governor casing.

This will cause a reduction in the speed of rotation of the worm shaft and results in the load being lowered at a comparatively uniform speed.

Should it be desired to stop the lowering 120 at any particular point, pressure on the actuating member 50 is removed and the springs 46 will return the brake arms 43 into contact with the brake wheel 42 and immediately prevent further lowering.

These brake arms 43 coacting with the 125 brake wheel 42 are sufficient to retain the load in elevated position until it is desired to lower the same.

It is believed that from the foregoing de- 130

scription, the operation and many advantages of the present invention will be readily understood.

Having thus described my invention, I 5 claim—

1. The combination with a lifting jack having a driving shaft adapted to be rotated in either direction; a disk revoluble therewith; a worm gear loosely mounted on said 10 driving shaft; a ratchet revoluble with said gear; pawls on said disk coacting with said ratchet; a worm adapted to be driven in one direction only by said worm gear; and a governor actuated by said worm.
- 15 2. The combination with a lifting jack having a driving shaft adapted to be rotated in either direction; a worm gear loosely mounted on said driving shaft; a worm meshing with said gear and adapted to be 20 driven thereby; a governor actuated by said worm; and a one-way driving connection between said driving shaft and said worm gear.
- 25 3. The combination with a lifting jack having a driving shaft adapted to be rotated in either direction; a worm gear loosely mounted on said driving shaft; a worm meshing with said gear and adapted to be 30 driven thereby; a governor actuated by said worm; a one-way driving connection between said driving shaft and said worm gear; and a removable bearing for the outer end of said driving shaft.
- 35 4. The combination with a lifting jack having a driving shaft adapted to be rotated in either direction; a worm gear loosely mounted on said driving shaft; a worm meshing with said gear and adapted to be 40 driven thereby; a governor actuated by said worm; a one-way driving connection between said driving shaft and said worm gear; and a removable member secured to the jack casing and provided with a bearing for the outer 45 end of the driving shaft.
- 45 5. The combination with a lifting jack having an operating shaft and a driving shaft; a pinion secured to said driving shaft; a gear secured to and revoluble in either direction with the operating shaft and 50 meshing with said pinion; a worm gear

loosely mounted on said driving shaft; a worm meshing with said worm gear; a governor actuated by said worm; and a one-way driving connection between said driving shaft and said worm gear.

55

6. The combination with a lifting jack having an operating shaft and a driving shaft; a pinion secured to said driving shaft; a gear secured to and revoluble in either direction with the operating shaft and 60 meshing with said pinion; a worm gear loosely mounted on said driving shaft; a worm meshing with said worm gear; a governor actuated by said worm; a ratchet secured to said worm gear; and pawls carried 65 by said driving shaft and coacting with said ratchet whereby rotation is imparted to said worm gear in one direction only.

7. The combination with a lifting jack having a revoluble operating shaft; a revoluble pawl-carrying member rotatable in either direction by said operating shaft; a worm gear alined with said pawl-carrying member; a ratchet carried thereby coacting with said pawls; a worm meshing with said 75 worm gear; and a governor actuated by said worm.

8. The combination with a lifting jack having a revoluble operating shaft; a revoluble pawl-carrying member rotatable in 80 either direction by said operating shaft; a worm gear alined with said pawl-carrying member; a ratchet carried thereby coacting with said pawls; a worm meshing with said 85 worm gear; a governor actuated by said worm; and a manually controlled brake wheel rotated in one direction only by said worm.

9. The combination with a lifting jack having a revoluble operating shaft; a revoluble pawl-carrying member rotatable in 90 either direction by said operating shaft; a worm gear alined with said pawl-carrying member; a ratchet carried thereby coacting with said pawls; a worm meshing with said 95 worm gear; and a manually controlled brake wheel rotated in one direction only by said worm.

WALTER E. LOMBARD.
